(57) CLAIM

We claim the ornamental design for a telescoping vent hood, substantially as shown and described.

DESCRIPTION

FIG. 1 is a perspective view of the telescoping vent hood in a retracted position shown in its environment.

FIG. 2 is a top plan view of the telescoping vent hood in the retracted position.

FIG. 3 is a front elevation view of the telescoping vent hood in a retracted position.

FIG. 4 is a rear elevation view of the telescoping vent hood in the retracted position.

FIG. 5 is a side elevation view of the telescoping vent hood in the retracted position, with the opposite side being a mirror image.

FIG. 6 is a perspective view of the telescoping vent hood on a reduced scale in a raised position relative to its environment.

FIG. 7 is a top plan view of the telescoping vent hood in the raised position.

FIG. 8 is a front elevation view of the telescoping vent hood in the raised position.

FIG. 9 is a rear elevation view of the telescoping vent hood in the raised position; and,

FIG. 10 is a side elevation view of the telescoping vent hood in the raised position, with the opposite side being a mirror image.

The broken line showing of environmental structure in FIGS. 1-10 is for illustrative purposes only and forms no part of the claimed design.
